UNITED STATES PATENT OFFICE

ALEXANDER O. VAN SICKELS, OF EAST HAVEN, CONNECTICUT.

GAME AND TOY.

1,161,552.

Specification of Letters Patent. Patented Nov. 23, 1915.

Application filed August 19, 1915. Serial No. 46,343.

To all whom it may concern:

Be it known that I, ALEXANDER O. VAN SICKELS, a citizen of the United States, residing at East Haven, in the county of New Haven and State of Connecticut, have invented a new and useful Improvement in Games and Toys; and I do hereby declare the following, when taken in connection with the accompanying drawings and the characters of reference marked thereon, to be a full, clear, and exact description of the same, and which said drawings constitute part of this application, and represent, in—

Figure 1 a side view of a top constructed in accordance with my invention, showing the tape engaged with the spindle preparatory to winding, and the crank handle in place. Fig. 2 a side view of the top, detached. Fig. 3 a side view of the top reverse of Fig. 1. Fig. 4 a side view of the top reverse of Fig. 2. Fig. 5 a sectional view on the line *a—b* of Fig. 1, enlarged. Fig. 6 a side view of the crank handle, detached. Fig. 7 a plan view of a counter adapted to be used in connection with my improved game or toy.

This invention relates to an improvement in games and toys, and particularly to those of the spinning-top variety, the object of the invention being to provide a spinning top with means for spinning it; and the invention consists in the construction hereinafter described and particularly recited in the claim.

In carrying out my invention, the top has a substantially square body 2 with a point 3, and a round stem 4. In one side of the stem is a notch 5, and in the center of the notch is a pin 6. As a means for spinning the top, I employ a handle 7 bifurcated at its outer end to form fingers 8 and 9 which have perforations adapting the fingers to set over the spindle 4; and to cause the top to rotate, I employ a tape 10 formed in one end with a gromet 11 which is adapted to enter the notch 5 and set over the pin 6. To assist in winding the tape around the spindle, I preferably form one side of the body with a hole 12 to receive one end of a crank handle 13. This crank handle is formed from a piece of wire doubled upon itself at one end to form a point 14 to enter the hole 12,

and at the other end to form a handle 15. The end of the wire 16 forming the point 14 is bent at right angles so as to form a stop 51 to limit the extent to which the crank handle may enter into the body. Preferably the sides of the body will bear certain numbers or words. As herein shown, one side is marked, "Take 1"; another side, "Give 1"; another side, "All 5"; and another side, "None".

To spin the top the handle is placed over the spindle and the gromet 11 placed over the pin 6. The wire crank-handle is then inserted into the body and by means of the crank-handle the body is turned so as to wind the tape around the spindle between the fingers 8 and 9 of the handle which form a guide for the tape; and by forming the 70 spindle with the notch 5, the gromet end of the tape will not project beyond the edge of the spindle so that the tape will be evenly wound around the spindle; and by using a flat tape instead of a string, all binding or 75 cramping is avoided. When the tape is sufficiently wound the crank-handle is removed and a sudden pull upon the tape will cause the top to rotate; and when the tape is unwound, it will slip off from the pin allowing 80 the top to drop away from the handle. After the momentum imparted to the top is exhausted, the top will fall on one side or the other, exposing the numbers or letters on the upper surface.

One use of a top is in connection with marbles, and if the top falls with the side uppermost bearing the mark, "Take 1", the spinner takes a marble. If another side comes up marked "Give 1", the spinner gives 90 a marble. If the side marked "All 5" comes up, the spinner takes all, or 5, as may be agreed; or if the side marked "None" comes uppermost, the spinner gets nothing. The top may also be used in connection with a 95 counter, as shown in Fig. 7 of the drawings, which consists of a graduated disk 17 having a pointer 18 pivotally mounted upon it, and adapted to sweep over the face of the disk to indicate various counts shown by the 100 faces of the top resting uppermost when the spinning is completed.

I claim:—

A game or toy of the class described, com-

prising a top-body formed at its lower end with a point, and at the upper end with a spindle, said spindle formed in one side with a notch and provided with a pin within said notch, combined with a handle having a bifurcated end perforated to set over said spindle, a flat tape formed with a gromet

adapted to engage with the pin in the spindle, said body formed in one side with a hole, and a wire crank handle adapted to enter said hole, whereby the body may be turned in the handle and the tape wound upon the spindle.

ALEXANDER O. VAN SICKELS.
